RESISTOR UNITS AND METHOD OF MAKING
THE SAMEAllan P. Charbonneau, Wauwatosa, Wis., assignor to
Cutler-Hammer, Inc., Milwaukee, Wis., a corporation
of Delaware

Application December 4, 1952, Serial No. 324,078

11 Claims. (Cl. 201—69)

This invention relates to resistor units and parts therefor, particularly resistor units of the type having stacked grid elements, and to a method of making the same.

In resistor units of this type there is appreciable expansion of the resistance grids and of the members upon which the grids are mounted. An object of my invention is to provide a resistor unit and a method of making the same in which such expansion is permitted without any buckling of the grids and further without distortion of the mounting structure for the unit.

Another object is to provide such a unit in which heating and consequent expansion of the members upon which the grids are mounted is minimized.

A further object is to provide such a unit, and a novel method of making the same, in which the foregoing objects and advantages together with ruggedness and dependability of the unit may be achieved at a minimum manufacturing cost.

These objects and advantages and others which will hereinafter appear are realized by the employment of a grid of novel construction which permits stacking of such grids in a manner permitting adequate cooling thereof without excessive heating of the grid supports, and by the provision of novel mounting means permitting lengthwise expansion of the grids and endwise expansion of the grid supports.

The accompanying drawings illustrate an embodiment of the invention which will now be described, it being understood that the embodiment shown is susceptible of various modifications in respect of structural details without departing from the scope of the appended claims.

In the drawings:

Figure 1 is a view in front elevation of a resistor unit embodying the invention;

Fig. 2 is an enlarged view in elevation of a floating-mounting plate;

Fig. 3 is an end elevational view of the unit shown in Fig. 1;

Fig. 4 is a view in elevation of a preferred form of the resistor grid employed;

Fig. 5 is a view in elevation of several resistor grids prior to finished assembly, the respective end lugs of each grid being bent in opposite directions, along the lines shown at X—X, in Fig. 4.

Referring to Figs. 1 and 3 of the drawings, there is shown a resistor unit of the type having stacked like resistor grids mounted upon parallel, spaced, insulated rods, for which rods a supporting frame is provided.

One of the like grids 10 is shown in side elevation in Fig. 4, the same having a flat body portion 10^a comprising a strip forming a series of closely spaced, oppositely projecting, parallel loops to form a relatively long, circuitous resistance path of substantially uniform cross sectional area. The body portion 10^a bridges a pair of lugs 10^b, each of which is provided with a perforation 11 and each of which extends beyond the same side edge of the body portion 10^a so that the center line connecting the

2

perforations 11 lies wholly outside the body portion for a reason to be hereinafter set forth.

Each grid 10 consists of an integral element punched from a sheet of suitable, resilient, resistance material such, for example, as nickel chromium, copper nickel, or chrome from alloys.

Referring again to Fig. 1, the grids 10 are mounted upon insulating tubes 12 and 13 which in turn are mounted upon support rods 14 and 15 respectively. Rod 14 and its tube 12 are inserted through the perforation 11 of one lug of each of the grids 10, and rod 15 and its tube 13 are inserted through the perforation 11 of the other lug of each of the said grids. By the use of spacers 16 and insulating washers 19 between successive pairs of lugs, the grids 10 are stacked in zigzag fashion to provide a continuous resistance path through the grids. As shown in Fig. 1 the respective pairs of adjacent lugs 10^b are pressed toward each other to afford a good electrical connection therebetween. The opposite end grids, which are designated 10^x and 10^y, have their respective terminal lugs 10^b pressed into good electrical engagement with the terminals 22, 22. The insulating washers 19 serve to insulate from each other the successive connected pairs of lugs 10^b at the upper and lower ends of the unit shown in Fig. 1.

Each of the terminals 22 is mounted upon tube 13 and is stacked along with the grids 10, spacers 16 and insulators 19. Terminals 22 are respectively provided with conductor attaching means of suitable form, as indicated at 22^a.

In addition, successive grids are arranged in reverse relationship so that the body portions of the respective successive grids are mounted on opposite sides of a transverse plane which, in Fig. 3, bisects rods 12 and 13.

The rods 12 and 13 are each longer than their respective insulating tubes 14 and 15 so that both ends of each extend beyond its respective tube. The exposed end rods are threaded. The stacked grids 10 and the spacers 16 and washers 19 are firmly held in position on the tubes at each rod end by an insulating washer 19, a compression washer 24, a tube retaining washer 25, a lock washer 26, and a nut 27. The nuts 27 are turned up tightly so that a good electrical connection is provided at the pressure joint between each pair of adjacently mounted lugs. If desired the lugs of each pair may be welded together to insure a good electrical connection between them.

If the grids, before assembly, are flat so that the lugs lie in the plane of the body portion, as in the grid illustrated in Fig. 4, tightening of nuts 27 will deform the grids so that each will have a double bow. After heating of the resistor, which will occur in testing or in normal use of the unit, the resistors will take a permanent set and have the normal assembled shape shown in Fig. 1.

When the grids are formed from heavy gauge material, the electrical connection at the pressure joint of adjacent grid lugs will be improved by bending the lugs at an angle with the plane of the grid. The lugs are bent in opposite directions, along the lines X—X of Fig. 4, so that they lie in parallel planes forming similar angles with the plane of the body portion. Also, the angle formed by each lug is somewhat greater than the angle at which the lug will be held when the stack is tightly assembled.

This is illustrated in Fig. 5 where the body portions of grids 30 and their respective lugs 30^a, 30^b are shown in their relative assembled positions prior to the clamping together of the lugs. The latter are oppositely bent from their respective body portions at an angle so that the lugs form an angle with one another from that end of each nearest its body portion. Upon tightening of the mounting rod end nuts 27, not shown in Fig. 5, each pair of lugs 30^a and 30^b will be pressed toward each other to

provide a pressure joint, the maximum pressure in which joint will occur at the ends of the lugs nearest their respective body portions since the grids are formed of resilient material. Thus a good mechanical and electrical connection is insured and the current, in flowing between successive grids 30, has a path of greatest area at the lugs, and the resistance variation and consequent heating at the joint are minimized.

Stacking the grids in zigzag fashion, with successive grids reversed as described, has the advantage that the respective body portions of the grids are widely separated for improved heat dissipation without the need for conducting spacers between lugs, which would double the number of pressure connections. Also the need for offset lugs or long leads from the lugs to the resistor body is obviated. Such stacking, and its consequent advantages, is permissible because of the novel good shape in which the body of the grid bridges its lugs in such manner that the body portions of successive grids when reversed cannot make contact even though the lugs are not offset or spaced. Moreover, the grid shape is such that both edges have like contour, except for minor variation in loop slots, thus permitting the grids to be punched from a strip of suitable resistance material with a minimum of waste.

The rods 12 and 13 are supported by the end panels 34 and 35 of the box or frame comprising, in addition, four tie rods or bolts 36 extending between the respective corners of the end channels to hold the latter in fixed spaced relationship as by means of inner and outer nuts 50, 50 and a lock washer 51. To prevent buckling of the grids due to their endwise expansion, rod 15 only is fixedly attached to the end channels 34 and 35; the other rod 14 being provided with a floating mounting. The threaded ends of rod 15 are secured by nuts 37 and lock washers 38 in openings near one edge of channels 34 and 35. Near the opposite end of each channel there is attached, by welding or otherwise, one of a pair of plates 39 having perforations 40, as best illustrated in Figs. 1 and 2.

The plates 39 are so positioned and welded or otherwise secured to the channels that, with the grids secured on the rods and with rod 15 secured in position by nuts 27 and 37, each end of rod 14 is disposed within one of the perforations 40. The latter are elongated in the plane bisecting said rods. Thus shaped, the perforations do not permit substantial lateral movement of rod 14 with respect to said plane, but do permit motion of rod 14 to vary the degree of separation of the rods as an incident to lengthwise expansion or contraction of the grids.

The rod 14 is of sufficient length to extend between both of the perforations but has a length slightly less than the distance between the channels 34 and 35. The channels prevent excessive endwise motion of rod 14 but do permit a degree of endwise expansion thereof as an incident to heating of said rod.

Provision is made for endwise expansion of rod 15 by cutting or slitting, at laterally spaced points 43, 43, one or both of the end channels 34, 35 to form a resilient tongue or tab portion 42 to which the rod 15 is rigidly attached, as shown in Fig. 3. The tongue 42 holds rod 15 rigidly thereto but permits endwise expansion of said rod, inasmuch as tongue 42 may be bent out of the plane of the channel 34. As will be understood, the resilient tongue formation may be provided by cutting or slitting the channel or channels in various alternative ways.

I claim:

1. An electrical resistance unit comprising a pair of parallel spaced insulating rods, a plurality of resistor grids each having a pair of mounting lugs and a central body portion bridging said lugs, said plurality of resistor grids being stacked in zigzag fashion between said rods and secured thereto in such a manner that the body portions of successive grids lie on opposite sides of the plane of said rods, a support for said rods comprising a pair of end members positioned in fixed spaced relation, each of

said members having secured thereto one of an opposed pair of attachment plates each having a perforation elongated in the plane of said rods to slidably engage an associated end of one of said rods, each of said members further having means for attaching thereto an associated end of the other rod.

2. A resistance unit according to claim 1, in which at least one of said pair of end members is provided with slits adjacent and on opposite sides of said means for attaching its associated end of said other rod to permit movement of a portion of said member as an incident to linear expansion of said other rod without affecting the spacing of said end members.

3. A resistance unit according to claim 2, in which said resistor grid lugs are bent and have resilience tending to separate the outer ends of adjacent lugs, together with clamping means to prevent such separation.

4. An electrical resistance unit comprising a plurality of resistor grids each having a pair of mounting lugs and a central body portion bridging said lugs, said resistor grids being stacked in zigzag fashion with each grid, other than the end grids, having one lug in juxtaposed conductive relationship with one lug of the next succeeding grid and the other lug in juxtaposed conductive relationship with one lug of the next preceding grid, the body portions of successive grids being reversed and lying on opposite sides of a transverse plane.

5. For a resistor comprising a plurality of resistor grids stacked between parallel support rods, a resistor support comprising a pair of end members having fixed spaced relation, means for attaching one of said rods to the respective end members, and an opposed pair of members each attached to one of said end members and having a perforation elongated in the plane of said rods to slidably receive an associated end of the other of said rods, said fixed spacing of said end members being somewhat greater than the length of said other rod, whereby the latter is free to move in said elongated perforation as an incident to expansion of said grids and endwise expansion of said rod last mentioned.

6. A device of the character set forth in claim 5, in which at least one of said pair of end members is provided with a flexible portion associated with said attaching means to permit linear expansion of said other rod without affecting the spacing of said end members.

7. In a resistance unit comprising a plurality of stacked resistor grids, a pair of support rods for supporting said grids, a pair of end members having spaced relation, means for attaching one of said rods to the respective end members, at least one of said end members being provided with a flexible portion associated with said attaching means to permit linear expansion of said rod without affecting the spacing of said end members.

8. The method of making an electrical resistance unit assembly of the type having stacked resistor grids mounted upon and extending between parallel insulated support rods, comprising the steps of punching a plurality of individual grids with perforated end lugs from resilient sheet resistance material, bending the end lugs of each grid oppositely out of parallel with said grid so that the corresponding ends of the grids are bent in like direction from their respective body portions, the angle formed in each case being greater than the angle required after assembly of the unit, stacking the grids in zigzag fashion with one of said rods inserted in each of the perforated lugs of said grids and compressing and clamping the lug ends of said stacked grids whereby said lug ends are held in parallel planes.

9. The method of claim 8 in which said successive grids are stacked in reversed relationship with respect to the plane of said support rods.

10. An electrical resistance unit comprising a pair of parallel spaced support rods, a plurality of punched resistor grids each having a pair of mounting lugs mounted on said support rods respectively and a central body

portion bridging said lugs, said resistor grids being stacked in zigzag fashion with the body portions of successive grids extending between said rods at angles of like degree on opposite sides of a plane perpendicular to the axes of the rods and with each grid, other than the end grids, having one lug connected in conductive relationship with one lug of the next succeeding grid and the other lug connected in conductive relationship with one lug of the next preceding grid, the body portions of successive grids being reversed and lying on opposite sides of a transverse plane.

11. An electrical resistance unit assembly comprising a plurality of punched resistor grids each having a pair of end mounting lugs and a body portion extending between said lugs and laterally therefrom, and a pair of parallel mounting rods spaced outwardly of the body

10

5

portion of said grids, said lugs being so secured upon said rods that the grids are stacked in zigzag fashion with the body portions of successive grids extending between said rods at angles of like degree on opposite sides of a plane perpendicular to the axes of the rods and with the body portions of successive grids on opposite sides of the plane of said rods.
